UNITED STATES PATENT OFFICE

RICHARD KAIER, OF CRANFORD, NEW JERSEY, ASSIGNOR TO THE SINGER MANUFACTURING COMPANY, OF ELIZABETH, NEW JERSEY, A CORPORATION OF NEW JERSEY

METHOD OF OPERATING CARBURIZING APPARATUS

Original application filed October 3, 1927, Serial No. 223,544. Divided and this application filed August 18, 1928. Serial No. 200,565.

This invention relates to carburizing apparatus for case-hardening steel parts. It has heretofore been the practice to pack the steel parts or work-pieces with the carburizing compound or powder in cold work-boxes, a batch of which were placed in a furnace and heated to and held at a certain temperature for a requisite time, at the expiration of which the work-boxes were removed from the furnace and dumped and allowed to cool before being re-packed. This practice necessitated the attention of several operatives, for example, one to pack the cold work-boxes, and others to attend to the removal of the work from the furnace, one operative removing a box, another removing the box cover, while the first dumps the box contents into a sieve manipulated by a third operative who shakes the sieve, allowing the spent compound to pass through, and dumps the work remaining on the sieve into an oil bath. In addition to the labor of several operatives, this practice necessitates the provision of several batch furnaces which occupy considerable floor space. Furthermore, considerable heat is lost due to the necessity of allowing the work-boxes to cool before re-packing them.

The present invention has for an object to provide an improved method of operating carburizing apparatus whereby a material saving may be effected in labor, floor space and fuel. Further objects of the invention will appear from the following description and claims.

The present method of operating carburizing apparatus was designed for the convenient handling of the work in all its various stages by a single operative who is enabled to produce an output equal to that heretofore produced by several operatives with an additional saving of floor space and fuel.

The furnace is preferably of the horizontal type with means for supporting and moving the work-boxes from a receiving station at one end of the furnace, along an outgoing run, thence across to a return run at the end of which is a discharge station adjacent the receiving station. The work-boxes, which are made of a heat-resisting alloy, such as nichrome, with removable covers, are prefer-

ably periodically propelled within the furnace by means of reciprocating pushers actuated automatically by suitable motor-driven cam-mechanism.

During the intervals between periodical operations of the pusher system, the operative may devote his attention to the packing of a thin-walled open-topped dummy box with work-pieces and carburizing compound. The dummy box is of a size to nest within a work-box and, when packed, may be slipped onto the horizontal supporting arm of a special work-box loading fixture.

The invention is preferably practiced as follows:

The operative, using a detachable handle, seizes and removes a hot work-box from the discharge end of the furnace and allows it to rest momentarily on a platform just outside the furnace door while the box cover is removed and held by a special cover-lifting fixture. The operative now dumps the box contents onto a vibrating inclined screen which allows the spent carburizing compound to fall through into a suitable receptacle while the work-pieces slide off of the lower end of the screen into an oil bath from which they are raised by an inclined belt-conveyor and deposited in a work-receptacle.

Immediately after dumping the hot work-box, the operative places the latter in an inverted position over the dummy box, inverts both boxes while in nested relation, and lifts the dummy box from the work-box, leaving the packed work-pieces and carburizing compound in the work-box which is returned to the cover-lifting fixture for restoration of the cover, after which the work-box is placed upon a platform just outside of the receiving door of the furnace for a momentary jarring operation to settle the box contents and dislodge any loose carburizing powder from between the box and cover, so that such powder will not fall from the box while in the furnace and accumulate therein, eventually clogging the combustion chamber. After the jarring operation, the box, while still red hot, is returned to the furnace; the box having been out of the furnace but a comparatively short time and having lost

but little heat during the rapidly accomplished dumping and repacking operations.

The present application is a division of my copending application, Serial No. 223,544, filed Oct. 3, 1927.

In the accompanying drawings Fig. 1 is a layout or plan view of the various pieces of apparatus suitably grouped for convenient operation by a single operative, according to the present method. Fig. 2 is a side elevation of the receiving and discharge stations at one end of the furnace. Fig. 3 is an end elevation of the furnace. Fig. 4 is a detail sectional view of a part of the special cover-lifting fixture at the discharge station of the furnace. Fig. 5 is a similar sectional view taken at right angles to the section shown in Fig. 4. Fig. 6 is a side elevation, partly in section, of the apparatus for receiving the work dumped from the work-boxes. Fig. 7 is a perspective view of one of the work-boxes and the detachable handle by means of which it is manipulated while out of the furnace. Fig. 8 is a perspective view of the dummy box used in loading the hot work-box. Fig. 9 is a side-elevation of the work-box loading fixture. Fig. 10 is a left end elevation of the upper end of the fixture shown in Fig. 9 before the packed dummy box is placed thereon. Fig. 11 is a similar view with the dummy box in place. Fig. 12 shows the empty hot work-box placed in inverted position over the dummy box. Fig. 13 shows, in full lines, both boxes after inversion of same and in dotted lines, the inverted dummy box lifted from the work-box. Fig. 14 is a sectional view on the line 14—14, Fig. 1, and Fig. 15 is an elevation of the transverse pusher operating mechanism viewed from the left, Fig. 14.

The furnace, shown at A, Fig. 1, is of the horizontal, gas-heated type having parallel longitudinally extending chambers 1, 2 within which are runways 3, 4 for the work-boxes 5, there being a cross-over 6 at the left-hand end of the furnace along which the work-boxes are transferred from one runway to the other. The work-boxes are introduced into the furnace through the doorway 7 at the receiving station at which is a platform 8. Within the furnace the work-boxes are propelled along the runways by the three reciprocating pushers 9, 10, 11 which are operated in sequence by suitable motor-driven cam-mechanism including the cam-wheels 9^a and 11^a carried respectively, by the shafts 9^b, 11^b which are driven by worm and gear connections 9^c, 11^c with a cross shaft 9^d having on it a pulley 9^e connected by the belt 9^f to a pulley 9^g on the counter-shaft 9^h carrying a second pulley 9ⁱ driven by the belt-connection 9^j from the motor 9^k. The cam-wheel 9^a has secured to its cylindrical wall the cam-inclines 9^m which reciprocate the follower 9ⁿ carried by the pusher 9. The cam-wheel 11^a

has secured to its cylindrical wall similar cam-inclines 11^m which reciprocate the follower 11ⁿ carried by the pusher 11. The pusher 10 has a rack on its under side engaged by a pinion 10^a on the shaft 10^b which is geared to the vertical shaft 10^c geared in turn to the shaft 10^d having secured to it the pinion 10^e meshing with the rack-bar 10^f. The bar 10^f is actuated by the face-cam 10^g on the cam-wheel 11^a.

At the end of the return runway 2 is the discharge station at which is a doorway 12 through which the work-boxes are removed after traversing the circuit through the furnace. A second platform 13, similar to the platform 8, is supported in front of the doorway 12. The doorway 7 is closed by a vertically sliding door 14 actuated by the lever 15 connected by the link 16 to the pedal-lever 17. The doorway 12 is closed by a vertically sliding door 18 actuated by the lever 19 connected by the link 20 to the pedal-lever 21.

The work-boxes 5 are made of a suitable heat-resisting material, such as nichrome alloy, and are formed with lateral grooves 22 for reception of the tines 23 of the detachable fork-like handle 24 by which the boxes 5 are manipulated while out of the furnace. Each box 5 includes a loose fitting cover 25.

Close to the doorway 12 through which the hot work-boxes are removed from the furnace in the inclined screen or sieve 26 onto which the contents of a work-box is dumped as soon as it is removed from the furnace. The screen 26 is shaken or vibrated by means of a suitable pneumatic hammer 27 to separate the spent carburizing compound from the work-pieces; the compound falling through the sieve 26 into the receptacle 28 and the work-pieces sliding into the hopper 29 of the oil-filled quenching tank 30. At the bottom of the hopper 29 is the inclined motor-driven belt-conveyor 31 which carries the work-pieces out of the tank 30 and delivers them to the work-receptacle 32. The screen 26 is vibrated periodically at the proper time in the cycle of operations through the action of a Benjamin air valve 27' controlled by the cam 27" of the furnace cam-mechanism.

Mounted on the tank 30 adjacent the screen 26 is the work-box loading fixture comprising a platform 33 and bearings 34 for a vertical slide-rod 35, the upper end of which extends above the level of the platform, and has fixed thereto the bearing 36 for the rotatable horizontal spindle 37 having on one end a head 38 from which extends a horizontal supporting bar 39 for the dummy box 40. Secured to the lower end of the slide-rod 35 is a cross-pin 41 which passes through the slot 42 in the pedal-lever 43 fulcrumed at 44 on the floor-bracket 45.

The dummy box 40, Fig. 8, is made of thin sheet metal of a size to nest within a work-box

5 and has secured externally to its bottom wall the guides 46 which slidably embrace the supporting bar 39.

Disposed adjacent the loading fixture platform 33 is the packing bench 47 including the hopper 48 which supplies the powdered carburizing compound. During the interval between work-box re-loading operations, the operative packs one of the dummy boxes 40 at the bench 47 with work-pieces and carburizing compound and slides the packed dummy box onto the supporting bar 39 of the reloading fixture, as shown in Fig. 9.

The operation of pusher 11 having advanced the leading box of the train on the return runway 4 of the furnace to a position in line with the doorway 12, the operative seizes the handle 24, raises the door 18 by pressure of the foot upon the pedal-lever 21, inserts the forked end of the handle in the lateral grooves in the work-box and removes the work-box from the furnace, resting it upon the platform 13 below the cover lifting fixture.

This fixture comprises a supporting frame 49 secured to the furnace and carrying a fulcrum 50 for an operating lever 51. The operating lever 51 passes through the bifurcated upper end of a vertically sliding sleeve 52 journaled in the frame 49. The lever 51 is formed with a slot 53 extending longitudinally of the latter and the sleeve 52 is formed with a vertical slot 54. A cross-pin 55 is passed through the slots 53, 54 and held in place by the washers 56 and pins 57. Secured to the lower end of the sleeve 52 is a horizontal bar 58 to the ends of which are fulcrumed the work-box cover-gripping levers 59. The upper ends of the levers 59 are connected by the toggle-links 60 to the center block 61 fixed to the lower end of the rod 62 extending upwardly within the sleeve 52 and pressing at its upper end against the cross-pin 55; the rod 62 being pressed upwardly by the spring 63 which engages the collar 64 fixed to the rod 62 within the sleeve 52. A trigger device in the form of a spring-pressed wedge 65 is mounted on top of the lever 51 in position for the wedge to enter between the lever 51 and the cross-bar 66 fixed to the sleeve 52 and hold the lever 51, pin 55, rod 62 and head 61 depressed, thus holding the gripper-levers in open position, as shown in Fig. 2.

The operative grasps and depresses the handle 51' of the lever 51, thereby moving the sleeve 52 and gripper-levers 59 downwardly into position for the lower ends of the levers 59 to engage under the work-box cover; the levers 59 being still open. The operative next pulls the hooked rear end of the trigger device, thus withdrawing the wedge 65 and permitting the spring 63 to shift the rod 62 and head 61 upwardly; the head 61 straightening the toggle-links 60 and closing the

gripper-levers into cover-seizing position. Release of the handle 51' permits the lever 51, gripper-levers 59 and box-cover to rise under the influence of the spring 66', Fig. 2, which pulls downwardly on one end of a lever 67 fulcrumed at 68 on the frame 49; the forward end of the lever 51 engaging under the lever 67 as shown in Fig. 4. It will be understood that by means of this fixture the operative may, with one hand, remove the cover from the hot work-box while the handle 24 of the work-box is held in the other hand. The box-cover may be restored to the work-box at the proper time by depressing the lever 51 until the collar 69, fast on the sleeve 52, striking the frame 49, arrests the downward movement of the sleeve 52. Further downward movement of the lever 51 depresses the cross-pin 55 in the slot 54 and shoves the rod 62 and head 61 downwardly, thus opening the gripper-levers 59 and releasing the cover. The wedge 65 moves under the influence of its spring to the position shown in Fig. 4 and holds the gripper-levers open for the next cover-lifting operation.

After the cover of the work-box has been removed and while it is held by the gripper-levers 59, the operative, using the work-box handle 24, dumps the contents of the work-box onto the vibrating screen 26 and then lowers the empty work-box in inverted position over the dummy box 40 on the supporting bar 39 of the box-loading fixture; as shown in Fig. 12. The operative then axially rotates the handle 24 180° to simultaneously rotate the work-box and dummy box, while in nested relation, about the axis of the spindle 37 to the position shown in Fig. 13. Pressure upon the pedal-lever 43 elevates the rod 35 and bar 39, thus withdrawing the dummy box from the work-box 5, as shown in dotted lines in Fig. 13, the packed contents of the dummy box resting undisturbed in the work-box. The operative now returns the packed hot work-box to the platform 13 for restoration of the box-cover and then rests the work-box and cover on the platform 8 where it is subjected momentarily to a jarring operation by a pneumatic hammer 70 carried by the lever 71 fulcrumed at 72. Depression of the handle 71 lowers the hammer 70 into working engagement with the cover of the work-box and draws down the bar 73 whose laterally bent upper end engages and opens the air valve 74 to start the operation of the hammer. This jarring operation settles the box-contents and dislodges any loose powder from between the box-cover and body, thus preventing the powder from falling into and eventually clogging the furnace combustion chamber. The work-box is then returned to the furnace through the doorway 7.

The invention is not to be understood as limited in its application to the particular

furnace and furnace equipment herein disclosed, and is independent of any particular or specific form of apparatus or furnace operating accessories or equipment.

Having thus set forth the nature of the invention, what I claim herein is:—

1. Method of operating carburizing apparatus comprising, packing the work-pieces and fresh carburizing compound in a cold dummy box of a size to nest with a work-box, removing a hot work-box from the furnace with the carburized work therein, dumping the hot work-box, nesting the hot empty work-box and packed dummy box, relatively separating said boxes leaving the packed contents of the dummy box, undisturbed in the work-box, and restoring the hot work-box to the furnace.
2. Method of operating carburizing apparatus comprising, packing the work-pieces and fresh carburizing compound in a cold dummy box of a size to nest with a work-box, removing a hot work-box from the furnace with the carburized work therein, dumping the hot work-box, placing the hot empty work-box in an inverted position over the packed dummy box, inverting both boxes while in nested relation, removing the dummy box leaving its packed contents in the work-box, and restoring the packed hot work-box to the furnace.

In testimony whereof, I have signed my name to this specification.

RICHARD KAIER.
